UNITED STATES PATENT OFFICE.

ERNEST SCHOFIELD, OF LEEDS, ENGLAND.

EXCAVATOR FOR TRENCHES, CUTTINGS, OR THE LIKE.

SPECIFICATION forming part of Letters Patent No. 703,972, dated July 1, 1902.

Application filed March 8, 1902, Serial No. 97,311. (No model.)

To all whom it may concern:

Be it known that I, ERNEST SCHOFIELD, a subject of the King of Great Britain and Ireland, and a resident of Leeds, in the county of York, England, have invented a certain new and useful Improvement in Excavators for Trenches, Cuttings, or the Like, (for which I have applied for a patent in Great Britain and Ireland, No. 18,061, bearing date September 10, 1901,) 5 of which the following is a specification.

The object of this invention is to provide means for rapidly, efficiently, and economically excavating and clearing trenches, cuttings, and the like, especially where the depth 15 is very considerable compared with the width, and to enable the depth and the inclination of the face to be adjusted with at most a momentary stoppage of the machine.

The invention provides for trenches of different widths being excavated by the machine and also for varying the character of the action of the tools on the working face of the trench. These objects I effect by a machine comprising a driving rod or rods carrying the excavating-tools, a thrust rod or rods attached at their lower ends to the driving rod or rods, a pair of cranks or crank-shafts, the upper part of the driving rod or rods and of the thrust rod or rods being attached by 25 clamp and hinge connections to the cranks or the cranks of the two crank-shafts, respectively, which latter are rotated in the same direction and at the same speeds by any suitable or convenient gearing; the whole being mounted on a platform on wheels carrying a bucket elevator to remove and raise the loosened material, and provided with mechanism for traveling the platform as the excavation proceeds. Such means are illustrated by the accompanying drawings, of 30 which—

Figure 1 is a side elevation, and Fig. 2 a plan.

A indicates the platform on which the machine is carried, the platform itself being mounted on wheels B, running on a pair of rails or tram-lines laid one on each side of the trench to be excavated.

C indicates the side frames, to which are secured the engine D or other motor driving the machine.

E is the boiler.

F is an inner foundation-plate provided with upstanding brackets G, to which the

lower ends of the four inclined posts H of the 55 braced elevator-frame are abutted and secured.

a are the driving-rod, to the front side of the lower half of which are secured the excavating-tools b, which in the drawings are 60 shown as bent-spike cutters, c being narrow spades. The form of the excavating-tools may be varied as deemed most suitable by the contractor. The extreme lower part of the rods a are preferably curved backward, 65 so as to bring the loosened material nearer to the lower end of the elevator, to be afterward referred to. The rods a are secured in clamping-pieces e, which are provided on the rear side with split sockets or journals d, 70 fitting the crank-pins of the crank-shaft f. By slackening the bolts of the clamping-pieces e the position of the rods a can be readily adjusted to suit the depth of the trench to be excavated. The crank-pins are 75 made considerably longer than the length of the sockets or journals d, so that by moving the washers g to the one side or the other or using narrower washers on both sides of the sockets or journals d and adjusting the 80 length of the tie-bolts h and using tool-bars m of different length the distance apart of the rods a—that is, the width of the trench or cutting—can be varied.

i are the thrust-rod, which are connected 85 at their lower ends to the lower part of the driving-rod a. The upper ends of these thrust-rod are connected to the crank-pins of a second crank-shaft j by clamping-pieces and split sockets or journals in exactly the 90 same manner as described for the connection of the driving-rod a to the crank-pins of the crank-shaft f.

The crank-shafts f and j are rotated in the same direction and at the same speed and 95 usually with both cranks in the same angular position. The motion of the points of the excavating-tools is in this case circular; but by altering the angular position of the cranks with respect to each other within short limits 100 the motion becomes elliptical, or if the cranks have unequal throws the motion is that of a distorted ellipse. By such alterations, therefore, the action of the tools may be varied from that of a scraping action to a percussive 105 action. By altering the position of the clamping-pieces e on the one pair of rods—say the thrust-rod—with correspondingly alter-

ing the position of the clamping-pieces on the other pair of rods—say the driving-rodsthe inclination of the working face may be varied.

5 The crank-shafts *f* and *j* are geared together by two large wheels *k* and *l* of equal size, and to obtain the same direction of rotation an intermediate wheel *m* is interposed between the two. The wheel *l* is driven by the pinion *o* on the shaft *p* of the motor. In 10 the plan the pinion *o* is shown slid sidewise on the shaft *p* out of gear with the wheel *l*, in which case the rods *a* and *i* are out of action.

15 The upper ends of the braced posts *H* carry the bearings for the top tumbler-shaft *q*, on one end of which is fitted the chain-wheel for the driving-chain *r* of the elevator.

20 *s* is the driving-shaft for the chain *r*, the opposite end of the shaft *s* having a wheel *t* gearing with a wheel *u*, mounted on the far side of the crank-shaft *f*. The lower tumbler-shaft *v* is carried at the lower end of the vertical beam *w*, the upper end of which slides in a box-guide formed by the plates *x* *y* *y*, to the former of which it can be bolted in 25 any position required by the depth of the trench to be excavated.

25 *z z* are the buckets, and *1 1* the links of the bucket-chain, the length of the chain being altered, if necessary, by the removal or addition of links and buckets to suit the depth of the trench to be excavated.

30 *2* is a chute (not shown in plan) into which the excavated material is thrown by the buckets as they pass over the top tumbler and is 35 thence discharged sidewise either onto the ground ready to be refilled into the trench or to be dumped into wagons for removal.

35 The provision for gradually advancing the excavator as the face of the trench is excavated consists of a worm-wheel *3* on the axle of the pair of rear wheels, a worm *4*, gearing with the same and fitted on the lower end of a vertical shaft *5*, bevel-wheels *6* and *7*, cross-shaft *8*, carrying a gear-wheel *9*, gearing with 45 a wheel *10* on the crank-shaft *f*. To move the platform *A* more rapidly, as may be required when the rods *a* and *i* are out of action, the gear-wheel *10* is slid, by means of the clutch *11*, out of gear with the wheel *9*, and the gear-wheel *12* on the shaft *p* of the motor is slid by its clutch into gear with the wheel *9*.

50 It will be evident that in the case of narrow trenchwork one driving-rod *a* only may suffice, while in the case of very wide work more than two driving and two thrust rods may be employed; also, that the exact arrangement of gearing as described and shown is not essential. Thus, for example, the wheels *k* and *l* may be made as chain-wheels connected by a chain-drive instead of by the intermediate pinion *m*.

55 Having now described my invention, what I claim, and desire to secure by Letters Patent, is—

1. In excavators of the type herein referred to, the combination of a platform *A* mounted

on wheels *B* a motor *D* motor-shaft *p*, a pair of crank-shafts *f* and *j* geared together and to the shaft *p* driving-rod *a a*, carrying excavating-tools *b*, and thrust-rod *i i* connected together toward their lower ends and respectively to the cranks of the shafts *f* and *j* a bucket elevator comprising buckets *z* link chain *1* adjustable vertical beam *w* carrying the lower tumbler-shaft *v* top tumbler-shaft *q* driving-chain *r* and driving-shafts and platform-traversing mechanism comprising worm-wheel *3* on the axle of one of the pair of wheels *B* worm *4* vertical shaft *5* bevel-wheels *6* and *7* cross-shaft *8* and connecting gear-wheels between the shafts *s* and *8* and the motor-shaft *p* respectively all substantially as herein set forth.

2. In excavators of the type herein referred to the combination of a platform *A* mounted on wheels *B* a motor *D* motor-shaft *p* a pair of crank-shafts *f* and *j* geared together and to the motor-shaft *p* driving-rod *a a* carrying excavating-tools *c b* thrust-rod *i i* connected at their lower ends to the driving-rod *a a* clamping and split journal-pieces *e d* a bucket elevator comprising buckets *z* link chain *1* adjustable vertical beam *w* carrying the lower tumbler-shaft *v* top tumbler-shaft *q* driving-chain *r* and driving-shaft *s* and gear-wheels *t* and *u* all substantially as and for the purposes specified.

3. In excavators the combination of so-called driving-rod *a* carrying excavating-tools *b c*, thrust-rod *i i* connected at their lower ends to the driving-rod *a* a pair of crank-shafts *f* and *j* geared to rotate in the same direction and clamping and split journal-pieces *e d* all substantially as and for the purposes specified.

4. In excavators the combination of a traveling platform *A* carrying a motor *D* and frames *C* with a pair of crank-shafts *f* and *j* mounted thereon so-called driving-rod *a a* carrying excavating-tools *b c* thrust-rod *i i* connected at their lower ends to the rods *a a* platform-traversing mechanism comprising worm-wheel *3* worm *4* vertical shaft *5* bevel-wheels *6* and *7* cross-shaft *8* and gear-wheels between the motor-shaft *p* and the crank-shafts *f* and *j* and the shaft *8* respectively substantially as and for the purposes specified.

5. In excavators the combination of so-called driving-rod *a a* carrying excavating-tools *b c* thrust-rod *i i*, cranks *f* and *j*, clamping and journal pieces *e d* bucket elevator comprising buckets *z* link chain *1* adjustable vertical beam *w* top and bottom tumblers and shafts *q v* and chute *2* motor *D* and connecting-gear between the motor and the crank-shafts *f* and *j* and top tumbler-shaft *q* substantially as set forth and illustrated.

ERNEST SCHOFIELD.
